(57) **CLAIM**

I claim the ornamental design for a card reader protector, as shown and described.

DESCRIPTION

FIG. 1 is a perspective view of a card reader protector, showing my new design in a closed configuration;

FIG. 2 is a front elevational view of FIG. 1;

FIG. 3 is a rear elevational view of FIG. 1;

FIG. 4 is a left-side elevational view of FIG. 1, the right-side elevational view being a mirror image thereof;

FIG. 5 is a top plan view thereof;

FIG. 6 is a bottom plan view thereof;

FIG. 7 is a perspective view thereof, illustrated in a partially open position;

FIG. 8 is a front elevational view thereof, illustrated in a fully open position;

FIG. 9 is a rear elevational view of FIG. 8;

FIG. 10 is a left-side elevational view of FIG. 8, the right-side elevational view being a mirror image thereof;

FIG. 11 is a top plan view of FIG. 8; and,

FIG. 12 is a bottom plan view of FIG. 8.

The broken lines showing an attachment loop and carabiner in FIG. 1, a card reader in FIG. 7, and a card reader insert exploded away from the card reader protector in FIGS. 7–10 and 12 depict environmental matter and form no part of the claimed design. The remaining broken lines represent stitching, and are part of the claimed design.
